United States Patent

Des. 239,518

Patented Apr. 13, 1976

239,518

PATIO BELL

Donald J. Beneteau, 1333 Front St. S.,
Amherstburg, Ontario, Canada

Filed Jan. 6, 1975, Ser. No. 538,818

Term of patent 14 years

Int. Cl. D10—06

U.S. Cl. D10—116

FIG. 1

FIG. 2

FIG. 3

FIG. 1 is a front elevational view of a patio bell showing my new design,

FIG. 2 is a side elevational view thereof, and

FIG. 3 is a cross-sectional view taken on line 3—3 of FIG. 2.

I claim:

The ornamental design for a patio bell, as shown and described.
